UNITED STATES PATENT OFFICE.

HARRY C. BUHOUP, OF CHICAGO, ILLINOIS, ASSIGNOR TO THE McCONWAY & TORLEY COMPANY, OF PITTSBURGH, PENNSYLVANIA, A CORPORATION OF PENNSYLVANIA.

DRAFT-RIGGING.

1,279,649.

Specification of Letters Patent. Patented Sept. 24, 1918.

Application filed July 2, 1917. Serial No. 178,074.

To all whom it may concern:

Be it known that I, HARRY C. BUHOUP, a citizen of the United States, residing at Chicago, in the county of Cook and State of Illinois, have invented certain new and useful Improvements in Draft-Rigging; and I do hereby declare the following to be a full, clear, and exact description of the invention, such as will enable others skilled in the art to which it appertains to make and use the same.

My invention relates to the construction of draft rigging for railway cars and is more particularly directed to certain structural features whereby the coupler and yoke are pivotally connected in a strong and reliable manner. The usual mode of pivotally connecting the coupler to the draft yoke is to employ a pivot pin which passes through suitable holes formed in the rear end of the coupler and in the forward end of the yoke. This pin is subject to very severe shearing strains in service and when broken in the pulling of trains allows the cars to separate, thereby causing delays and considerable damage to equipment. By my construction the use of a separate pivot pin is dispensed with and the pivotal connection between the yoke and the coupler is formed in a simple and efficient manner affording strength, security and durability to the construction.

Generally stated, the principal feature of the invention involves the combination with a coupler having pivot lugs or bosses at its rear end, of a draft yoke formed with a hooded forward end and having a plurality of curved bearings adapted to coöperate with the corresponding pivot lugs, at least one of the curved bearing members being detachable from the yoke so as to be forwardly removable, and means being provided for maintaining said removable bearing member or members in assembled relation.

There are other features of invention relating to special matters of form and elemental combinations of the parts, as will hereinafter appear and be pointed out in the claims.

In the drawings which illustrate the best mode in which I contemplate applying the principle of my invention,

Figure 1 is a view, partly in elevation and partly in vertical central section, showing a construction embodying my invention, the

forward portion of the car coupler and the rear portion of the draft yoke being omitted.

Fig. 2 is a horizontal central section of the construction illustrated in Fig. 1, the car coupler being shown in plan.

Fig. 3 is a front elevation of the construction shown in Figs. 1 and 2, the coupler being in transverse section.

Fig. 4 is a detail view showing in longitudinal vertical section the forward portion or hooded end of the draft yoke illustrated in the preceding views.

Fig. 5 is a detail plan view of one of the curved bearing members.

Fig. 6 is a plan view of a modified form of the invention, the forward part of the coupler and the rear end of the yoke being omitted.

Fig. 7 is a vertical longitudinal portion of the construction shown in Fig. 6, the coupler being in elevation.

Fig. 8 is a front elevation of the construction illustrated in Figs. 6 and 7, the car coupler being shown in transverse section.

Fig. 9 is a section on the line 9—9, Fig. 7.

Fig. 10 is a detail plan view of the curved bearing member that is employed in the modified construction.

Figs. 11 and 12 are respectively a plan view and a side elevation of a modified form of car coupler well suited for carrying out the invention.

Figs. 13 and 14 are respectively a plan view and a side elevation of the rear portion of still another form of car coupler suitable for practising my invention.

In the form of construction illustrated in Figs. 1 to 5, inclusive, 1 indicates the coupler and 2 is the draft yoke of a draft rigging. The coupler is provided with a head (not shown) for interlocking with a mating coupler and the yoke is provided with parallel arms 3, 3 that are connected at their rear ends in the usual way. The draft yoke is adapted to coöperate with the ordinary springs and followers (not shown) or other well-known cushioning unit. The coupler 1 is preferably provided a short distance in advance of its rear end with oppositely extending cylindrical pivot lugs or circular bosses 4, the rear end of the coupler being also curved, as at 5, concentric with the said pivot lugs.

The forward end of the draft yoke 2 is

- hooded or socketed, being formed with side walls 6 integrally uniting the top and bottom walls 7. The yoke is also preferably provided with a transversely extending wall 8 which is adapted to engage the forward follower (not shown) of the usual arrangement of springs and followers within the yoke. A wall such as 8 not only braces and ties together the walls 6 and 7 of the draft yoke, thus increasing the strength of the structure, but also receives the buffing shock from the car coupler 1 and communicates it to the forward follower, for which it affords a bearing of extended area. The inner faces 9 of the lateral walls 6, 6 of the yoke diverge outwardly so that the coupler receiving socket of the yoke is of a flaring form permitting the coupler to swing laterally when the train is passing around a curve.
- 10 The interior faces of the top and bottom walls 7 of the yoke, instead of being flat throughout, are preferably fashioned with longitudinally extending channels 10 which are of substantially the same dimensions, 15 both in respect of depth and width, as the pivot lugs 4, and which receive the said pivot lugs. These channels 10 in conjunction with the flaring of the side walls 6 give to the coupler receiving socket of the draft yoke 2 a 20 cruciform cross-section which is very strong and rigid.
- 18 Coöoperating with the curved forward faces of the pivot lugs 4 are bearing members 11 having correspondingly curved bearing faces. These members 11 fit in the longitudinally extending channels 10 of the draft yoke, being thereby maintained against lateral movement. Their forward faces respectively engage transversely extending bars or keys 12 which are removably mounted on the draft yoke so as to stand in horizontal alinement with the bearing members 11 in the path of removal of the pivot lugs 4 of the coupler. The draft yoke is 25 provided with suitable holes 13 or openings for the reception of the locking bars 12, which latter may be conveniently retained in assembled position by means of cotters 14.
- 30 In assembling the construction hereinbefore described, the coupler 1 is first inserted in the socketed end of the draft yoke 2, the bearing members 11 are then placed in position and finally the bars or keys 12 are inserted in the apertures 13 of the head and 35 secured in place by means of the cotters 14.
- 35 In the modification of my invention illustrated in Figs. 6, 7, 8, 9 and 10 of the drawings, the coupler 1 is provided with pivot lugs 4 and its inner end 5 is curved concentrically with the pivot lugs, identically the same as in the construction heretofore described. The draft yoke 2^a, though of hooded or 40 socketed form, differs somewhat in details of construction from the draft yoke 2. Instead of being provided with curved bearing 45 members 11 both of which are removable, the yoke 2^a preferably has but a single removable bearing member 11^a, the curved bearing 11^b coöperating with the upper pivot lug 4 being formed as an integral part of 50 the draft yoke. Since only one removable bearing member is employed in this form of construction, a single transversely extending removable key or bar 12^a, corresponding to the locking bars 12, suffices to 55 maintain the parts in assembled position. A cotter 14^a may be employed to prevent the headed bar 12^a from accidentally becoming disassociated from the draft yoke 2^a.
- 60 As in the case of the construction heretofore described, the socketed end of the draft yoke 2^a is, as shown, flared laterally to permit the coupler to execute the desired swinging movements. The vertical height of the socket into which the coupler 1 fits is sufficiently great to allow the coupler to be lowered until its upper pivot lug 4 clears the shoulder or bearing member 11^b of the draft yoke when the key 12^a has been removed and the supporting bearing 11^a has been withdrawn forwardly through the mouth of the coupler receiving socket of the draft yoke. As well shown in Fig. 7 of the drawings the pivot bearing member 11^a extends under the stem of the coupler and under the lower 65 pivot lug 4 thereof, thus supporting the coupler in elevated position. It is also preferred to extend the bearing member 11^a forwardly beneath the bar 12^a so that it may bear against the sides of the yoke at its forward end and thus be sustained against lateral swinging or shifting with respect to the yoke.
- 70 In assembling this modified construction the coupler 1 is inserted in the flaring socket at the forward end of the draft yoke 2^a and its upper pivot boss 4 is brought into engagement with the corresponding curved bearing 11^b. The bearing member 11^a is then entered in the mouth of the yoke socket and 75 pushed rearwardly to assembled position, after which the transversely extending locking bar or key 12^a is put in place.
- 80 Figs. 11 and 12 illustrate a modified construction of coupler which may be advantageously employed. In the form of coupler shown in these figures the stem of the coupler has a filler block 15 that is interposed between and riveted or bolted to upper and lower plates 16. Pivot lugs 4^a are cast 85 integral with the filler at its rear end.
- 85 Still another manner of fashioning the car coupler is illustrated in Figs. 13 and 14. In the construction there illustrated the pivot lugs 4^b are formed integral with plates 17 90 which are riveted to an interposed filler member 18.
- 95 The advantage in employing a coupler of either of the described modified forms is that, being a built-up or composite structure 100

instead of a single integral unit, the coupler if damaged seldom requires to be completely replaced, but may usually be repaired by replacing the part of it which is injured or broken.

5 I claim:

1. In a draft rigging, the combination with a coupler having pivot lugs, of a draft yoke provided with a hooded forward end, 10 curved bearing members co-operating with said pivot lugs, at least one of said bearing members being forwardly removable, and means in horizontal alignment with one of said pivot lugs for maintaining the adjacent bearing member in assembled position.
- 15 2. In a draft rigging, the combination with a coupler provided with oppositely disposed pivot lugs, of a yoke having a socketed forward end, means for pivotally connecting said coupler and yoke, said means engaging said pivot lug, and transversely removable means located in the path of removal of said lugs for holding said first named means in engagement with said lugs.
- 20 3. In a draft rigging, the combination with a coupler provided with oppositely disposed pivot lugs, of a draft yoke provided with a coupler receiving socket, means for pivotally connecting said coupler and yoke, said means including a plurality of laterally extending bars carried by said yoke and located forwardly of said pivot lugs.
- 25 4. In a draft rigging, the combination with a coupler, of a draft yoke, means for pivotally connecting said coupler and yoke, said means comprising a plurality of bearing members each of which is adapted to engage a pivot lug on the said coupler, and 30 a plurality of bars each interposed between an adjacent bearing member and a portion of said yoke.
- 35 5. In a draft rigging, the combination

with a coupler provided with pivot lugs adjacent the inner end thereof, of a draft 45 yoke provided with a forwardly open laterally flared socket, the inner end of the coupler being adapted to be inserted into said socket, bearings engaging the forward faces of said pivot lugs, and means for holding said bearings in engagement with said lugs, whereby said coupler and yoke are pivotally connected.

50 6. In a draft rigging, the combination with a coupler having pivot lugs at its inner end, of a draft yoke having a forwardly open laterally flaring socket, means for pivotally connecting said pivot lugs to said yoke, said means including a plurality of bearing members insertible into said socket 60 after the insertion of said coupler and each adapted to engage the forward face of one of said pivot lugs.

65 7. In a draft rigging, the combination with a coupler having a plurality of pivot lugs, of a draft yoke having a hooded forward end, means for pivotally connecting said coupler and yoke, said means including a plurality of curved bearing members, removable means for preventing forward movement of the bearing members relative to said yoke, and means for preventing a rearward movement of said coupler with respect to said yoke.

70 8. In a draft rigging, the combination with a coupler having pivot lugs, a draft yoke, and curved bearing members removably mounted on said yoke and respectively co-operating with the said pivot lugs of the coupler, said bearing members being interposed between said pivot lugs and the forward end of said yoke and being removable independently of said yoke.

In testimony whereof I affix my signature.

HARRY C. BUHOUP.
